UNITED STATES PATENT OFFICE.

ROBERT LEE EVERETT, OF SCOTTSBLUFF, NEBRASKA.

DITCHING-MACHINE.

No. 841,815.

Specification of Letters Patent.

Patented Jan. 15, 1907.

Application filed February 26, 1906. Serial No. 303,026.

To all whom it may concern:

Be it known that I, ROBERT LEE EVERETT, a citizen of the United States, residing at Scottsbluff, in the county of Scotts Bluff and State of Nebraska, have invented a new and useful Ditching-Machine, of which the following is a specification.

This invention relates to ditching-machines; and it has particular reference to an improved machine of this class for forming small ditches, channels, or trenches for sub-irrigation purposes, said trenches being for the purpose of conveying water from the main irrigating-ditches over the field that is to be irrigated without making it necessary to completely overflow or inundate the same, the object of the invention being to provide a device of this class which shall possess superior advantages in point of simplicity, durability, and general efficiency.

With these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of the invention, it being, however, understood that no limitation is necessarily made to the precise structural details therein exhibited, but that changes, alterations, and modifications within the scope of the invention may be made when desired.

In the drawings, Figure 1 is a perspective view of a ditching-machine constructed in accordance with the principles of the invention. Fig. 2 is a longitudinal sectional view of the same.

Corresponding parts in both the figures are indicated throughout by similar characters of reference.

A suitably-constructed frame 1, preferably of rectangular shape, is provided with bearings for a shaft 2, carrying a plurality of lenticular or double-convex disks 3, which are mounted adjustably upon said shafts, as by means of set-screws 4 extending through the hubs 5 of the disks. The latter may thus be spaced upon the shaft at various distances apart, and any desired number of the disks may be mounted upon the shaft.

The frame is provided with bearings 6 for a rock-shaft 7, having a crank 8, upon which are mounted a plurality of standards 9, car-

rying bull-tongue plows 10 or furrow-openers of any approved construction, one of the standards being arranged directly in front of each of the disks 3. The standards 9 are 60 preferably provided with eyes 11, whereby they are pivoted upon the crank of the rock-shaft, and the latter is preferably provided with collars 12, having set-screws 13, whereby they may be secured for the purpose of retaining the standards at various adjustments in front of the disks. Upon the front side of the frame there are secured a plurality of straps or loops 14, serving to confine the standards 9, said loops being preferably inclined in a forward and upward direction, so that they will not interfere with the vertical adjustment of the standards 9. In order to effect such adjustment, a lever 15 is provided, said lever being pivoted upon a quadrant 16, 65 which has been illustrated as secured upon a tongue 17, which extends longitudinally through the frame and which carries a seat 18 for the driver or operator. The fulcrum of the lever is in approximate alinement with 70 the bearings of the rock-shaft 7, and one end of said lever is pivoted upon the crank 8, while the other end of the lever, which constitutes a handle, carries a stop member 19, 75 engaging the quadrant 16 for the purpose of retaining the lever and related parts at various adjustments.

By manipulating the lever 15 the cranked rock-shaft may be operated so as to raise or lower the plows. When the latter are lowered, they will form furrows in the soil in advance of the disks, which latter, traveling in the furrows, will deepen the said furrows and compress and compact the soil. These ditches or trenches are made to connect the 95 irrigating-ditches, and they will serve to convey the water from the irrigating-ditches over the portion of the field in which the subirrigating-ditches are formed.

By the use of this invention much water 100 will be saved and much labor will also be saved in the preparation and cultivation of the soil, which latter will be kept mellow and in good condition for the crops.

Having thus described the invention, what 105 is claimed is—

1. In a ditching-machine, a rock-shaft, blade-carrying standards pivotally engaging and laterally adjustable upon a crank formed upon said rock-shaft, means for oscillating 110 the rock-shaft, and loops confining and guiding the standards.

2. In a ditching-machine, a rock-shaft having a crank, blade-carrying standards pivotally engaging and laterally adjustable upon said crank, means for oscillating the rock-shaft and for securing it at various adjustments, means for guiding and confining the standards, and furrow-engaging, soil-compacting members supported for rotation in rear of the standards.
3. In a ditching-machine, a rock-shaft, blade-carrying standards pivotally engaging and laterally adjustable upon a crank formed

upon said rock-shaft, means for oscillating the rock-shaft, loops confining and guiding the standards, a shaft located behind the 15 plows and laterally - adjustable wheels located upon the last-said shaft.

In testimony that I claim the foregoing as my own I have hereto affixed my signature in the presence of two witnesses.

ROBERT LEE EVERETT.
